CLAIM

The ornamental design for a therapeutic animal mastication device, as shown and described.

DESCRIPTION

FIG. 1 is a perspective view of a therapeutic animal mastication device according to the present invention.

FIG. 2 is a front elevation view of the therapeutic animal mastication device of FIG. 1, to which a rear elevation view is identical.

FIG. 3 is a left side elevation view of the therapeutic animal mastication device of FIG. 1, to which a right side elevation view is identical.

FIG. 4 is a top plan view of the therapeutic animal mastication device of FIG. 1; and,

FIG. 5 is a bottom plan view of the therapeutic animal mastication device of FIG. 1.

The broken lines in the drawings depict portions of the therapeutic animal mastication device that form no part of the claimed design.
